UNITED STATES PATENT OFFICE.

HARRY F. GLAIR AND EDWARD J. WONNACOTT, OF WHITING, INDIANA, ASSIGNEES TO
STANDARD OIL COMPANY (OF INDIANA), OF WHITING, INDIANA, A CORPORATION
OF INDIANA.

ART OF FILTRATION.

Application filed August 11, 1920. Serial No. 402,609.

To all whom it may concern:

Be it known that we, HARRY F. GLAIR and EDWARD J. WONNACOTT, citizens of the United States, residing at Whiting, in the county of Lake and State of Indiana, have invented a new and useful Improvement in the Art of Filtration, of which the following is a specification.

The present invention relates to the art of filtration, and more particularly to the filtration of paraffine wax or other wax or fusible substance from chilled oil or other vehicle. It will be fully understood from the following description thereof, illustrated by the accompanying drawing, in which:

Figure 1 is an elevation of a filter press adapted for use in connection with the present invention, certain of the detailed elements of construction not being shown therein;

Figure 2 is an elevation of the end portion of a filter press, showing a construction adapted for use in connection with the present invention;

Figure 3 is a transverse section through the press shown in Figure 2, one of the filter faces being shown in elevation, and partially broken away;

Figure 4 is a detail elevation of a ring provided with a heating element used in connection with the present invention, and showing the means of its connection with the manifolds supplying the heating medium and its support within the filter press;

Figure 5 is a detailed view showing the arrangement of manifolds for the heating medium; and,

Figure 6 is a vertical sectional view on the line 6—6 of Figure 3, through the filter press plates.

Referring more particularly to the drawings, the numeral 10 indicates a filter press resting upon a suitable floor or foundation 11 and provided with a stationary standard 12 at one end and a movable end plate 13 at the other, to which pressure is applied by means of a suitable device, for example, the hydraulic press 14. The movable end plate as well as the various plates and elements making up the filter press construction are supported vertically upon the longitudinally extending rails 15.

The filter press body is made up of a

series of filter members, each of which comprises two filtering surfaces with a space between from which filtered material is drained, alternating with separating rings forming spaces into which the oil to be filtered is introduced and in which the wax is deposited. As shown most clearly in Figs. 3 and 6, the filter supporting members comprise a ring 16, provided at each side with a projection 17 by which it is supported upon the rails 15, 15 and upon each side of the ring 16 is attached a perforated metal disc 18, having imperforated edges and provided centrally with enlarged aligned openings. The filters, consisting of heavy canvas or duck cloths 19, 19 are supported upon the metal plates 18, 18, the filter cloths upon the two sides of the support formed by these plates being sewed together at intervals around the outer edges of the ring, as shown at 20, and likewise within the openings in the metal plate 18 as indicated at 21. The central openings in the filter cloths permit free passage of oil through the device, the sewing together of the cloth around the central opening, as indicated at 21, preventing admission of unfiltered oil into the space 22 between the filters within the ring 16. Each of the rings 16 is provided with a suitable drainage opening 23, through which filtered oil may flow out of the space 22 within the ring 16.

The respective filter bodies formed by the rings 16, the perforated metal support 18 and the filters 19 are spaced apart by rings 24, likewise mounted upon the rails 15 by means of suitable lateral projections 25, 25. The use of these rings 24 provides spaces 26, 26 between the opposite filter faces of successive filter plates, into which spaces the oil may freely flow as hereinafter described, and in which spaces the filtered wax is deposited upon the surfaces of the filters 19, 19. As shown most clearly in Figures 4 and 6, coils 27 are provided within the spaces 26, being secured to the spacing rings 24, the ends of these coils passing through suitable openings drilled in the rings 24 and being bent as indicated at 28 into suitable position for convenient connection with manifolds by which heating and cooling media may be supplied.

In order to supply and remove the heat-

ing or cooling medium the manifolds or headers 29 and 30 extend longitudinally of the press above and below it respectively. At regularly spaced intervals, sub-headers 31, 31 branch off from the main headers 29 and 30 and extend parallel thereto.

These sub-headers 31, 31, are provided with nipples 32, from which connection is made to the curved portions 28 of the coils 27 outside of the ring 24, for example, by means of suitable flexible connectors 33, 33. The manifolds 28 and the sub-headers and connections therewith serve for the supply of the heating or cooling medium, and the lower header 30 with its various connections serves for the withdrawal or removal of the heating or cooling medium.

Removal of wax and oil after these materials have passed out of the filter press is effected by the means most clearly indicated in Figure 3. A well is formed below the filter press, in which are provided two adjacent longitudinally extending troughs 34 and 35, the former of which serves for conveying away filtered oil and the latter for conveying away the slack wax filtered from the oil in the press. To facilitate this removal, the trough 35 may be suitably provided with a screw conveyor 36. The filtered oil passing out of the trough 34 is conveyed away through the pipe 37. Longitudinally extending inclined plates 38, 38 below the filter press serve to guide the oil or wax passing out of the press, as the case may be, to the movable angular deflector 39, by which the material is guided to the proper trough. This angular deflector 39 is pivoted at 40, and has two angularly disposed sections 41 and 42, the former of which serves, when in the position indicated in full lines in Figure 3, to guide the material coming from the press into the trough 34, and the latter, when in the position shown in dotted lines in Figure 3, to guide the material coming from the filter press into the wax trough 35. The movable deflector 39 is operated by means of cables 43, which are attached to the longitudinally extending rotatable shaft 44 operable by crank 45.

In operation, chilled oil containing the paraffine wax in suspension is conveyed into the filter press through the supply pipe 46. It enters and fills the press, passing through the central openings through the filter cloths 19, and filling the spaces 26, 26 throughout the press between the filter plates. The oil is forced through the filter cloths 19 into the spaces 22 between them, the cloths being supported substantially uniformly over their entire surfaces by the plates 18, and the pressure or head of the oil over the filtering surfaces being approximately the same at all points. From the spaces 22 the filtered oil drains through the openings 23 out of the press, being guided by the plates

38, 38 and the deflector 39 into the oil trough 34. The wax filtered out from the oil deposits in the spaces 26, 26 between the filter plates. As soon as these spaces become substantially filled with slack wax the supply of chilled oil is cut off. Steam is then admitted into the header 29 through a suitable cock controlling the same, from which it passes into the various sub-headers 31 and from them into the coils 27 in the wax spaces 75 or chambers 26. The steam thus introduced melts the wax contained in these chambers, which after melting, flows through the filter cloths 19 into the spaces 22 within the filter plate and from there out of the press 80 through the openings 23. The melted wax is guided by the plate 38 and the deflector 39 into the wax trough 35, out of which it is conveyed by the conveyor 36. The issuing steam and condensate therefrom are withdrawn through the header 30. After the wax has been removed from the press, chilled oil may be immediately introduced as in the manner above described, in which case the oil which is initially passed through and which serves to chill the press must be again chilled and passed through the press, or the press may be initially cooled by passing cold oil preferably filtered, through the header 29, the coils 27 and out through the header 30 before introducing the chilled oil for filtration through the main pipe 46.

Although the present invention has been described in connection with a specific example of its operation and a construction capable of carrying out the same, it is not intended that the details set forth shall be regarded as limitations on the scope of the invention except in so far as included in the accompanying claims.

We claim:

1. In apparatus for filtering wax from chilled oil, in combination, a filter surface, means for uniformly supporting said surface, means for forcing chilled oil through said surface, thereby depositing wax thereupon, and heating means adjacent the filter surface and upon the side opposite the support thereof for applying heat to the wax deposited thereupon.

2. In wax filtering apparatus, a filtering septum, a confined chamber on each side thereof, means for supplying chilled oil into one of said chambers, means for withdrawing filtered oil from the other of said chambers, a coil in the first of said chambers in proximity to the filtering septum, and means for supplying heating or cooling media to said coil.

3. In wax filtering apparatus, a plurality of spaced uniformly supported filtering septa, means for forcing chilled oil into the alternate chambers or spaces between said septa, means for withdrawing filtered oil from the others of said chambers, coils in the cham-

bers between said filtering septa into which chilled oil is supplied, and means for introducing heating or cooling media into said coils.

- 5 4. In a filter press, a plurality of aligned filter plates, each comprising spaced filters and means for uniformly supporting said filters, means for removing oil from the spaces within said filter plates between said filters, spacing rings between said filter plates forming wax spaces, coils within said rings substantially parallel to the filters, means for introducing heating or cooling media into said coils, and means for introducing chilled oil into said wax spaces.
- 10 5. In a filter press, a plurality of aligned filter plates each comprising spaced filters

and means for uniformly supporting said filters, means for removing oil from the spaces within said filter plates between said filters, spacing rings between said filter plates forming wax spaces, coils within said rings substantially parallel to the filters, means for introducing heating or cooling media in said coils, said coils being provided with projecting inlets and outlets, headers connected respectively with said inlets and outlets whereby heating or cooling media may be introduced into and withdrawn from the coils, and means for introducing oil into the wax spaces.

HARRY F. GLAIR.

EDWARD J. WONNACOTT.
